UNITED STATES PATENT OFFICE.

CHARLES DE KOCK, OF WHITE LAKE, SOUTH DAKOTA.

SPARK ARRESTER.

Application filed October 7, 1924. Serial No. 742,187.

To all whom it may concern:

Be it known that I, CHARLES DE KOCK, a citizen of the United States, residing at White Lake, in the county of Aurora and

5 State of South Dakota, have invented certain new and useful Improvements in Spark Arresters, of which the following is a specification, reference being had to the accompanying drawings.

10 This invention relates to spark arresters, and has for an important object thereof the provision of a device of this character which may be very cheaply produced and readily installed upon the locomotive.

15 A further object of the invention is to provide a device of this character in which a minimum amount of back pressure is placed against the exhaust of the gases from the locomotive stack.

20 A further object of the invention is to provide in a device of this character a novel and improved means for arresting the force of blowing cinders, which has been imparted thereto by the gases exhausting from the

25 stack, so that they may fall to the right-of-way by gravity and not be blown high into the air so that they are carried out into fields where they are likely to cause fires.

20 A further and more specific object of the invention is to provide a novel and improved baffling means for the gases so that their forces are expended without producing an undesirable back pressure.

These and other objects I attain by the 35 construction shown in the accompanying drawings, wherein for the purpose of illustration is shown a preferred embodiment of my invention and wherein:—

Figure 1 is a side elevation of a stack having a spark arrester constructed in accordance with my invention applied thereto, the arrester being shown in dotted lines in inoperative position;

Figure 2 is an enlarged detail sectional view showing the stack-attached supports by means of which the arrester is connected with the stack;

Figure 3 is an enlarged fragmentary side elevation at right angles to that shown in 50 Figure 1, a portion of the casing being broken away to show the baffles;

Figure 4 is a vertical sectional view taken through the spark arrester and stack;

Figure 5 is a transverse sectional view 55 through the spark arrester on the line 5—5 of Figure 4.

Referring now more particularly to the drawings, the spark arrester comprises a cylindrical casing 10 adapted to be secured above the upper end of the locomotive stack 11. As a preferred means of attachment, I employ the structure more specifically illustrated in Figure 2. In this figure the rolled reinforced edge of the upper end of the stack is indicated at 12. Beneath this stack 15 a clamping band 13 is arranged. Two U-shaped supporting members are provided, generally indicated at 14, the bend of the U-shaped members being such that they conform to the rolled edge 12 of the stack as shown. The end of the lower arm 15 of the U-shaped member is provided with a downwardly directed flange 16 extending between the clamping band 13 and the stack wall, so that this clamping band serves to 70 maintain the U-shaped member in engagement with the rolled edge. The upper arm 16 of the U-shaped member is provided with a vertically and upwardly extending flange 17, the upper end of which is provided with spaced rolled eyes 18 receiving therebetween a single eye 19 formed on the lower end of a strap or bar 20, the upper end of which is rigidly secured to the cylinder 10, as at 21. The combined lengths of 75 the flange 17 and bar 20 beneath the member 10 are preferably such that the lower end of the cylinder is supported above the upper end of the stack with an intervening 80 space of about one foot.

Within the lower end of the cylinder 10 is arranged a trunco-conical sleeve 22, the larger end of which is disposed downwardly and provided with a flange 23 which is secured to the inner wall of the cylinder 10. 95 The cylinder, in alignment with the trunco-conical sleeve 22, is provided in its side wall with a plurality of circumferentially spaced openings 24 the upper ends of which are arranged at approximately the level of 100 the upper end of the sleeve 22, and the lower ends of which coincide with the lower end of this sleeve. The truncation of the sleeve forms a central opening 25 above which is supported an inverted conical baffle 26 having its axis coinciding with the axis of the cylinder, supports for this baffle preferably 105 extending between the baffle 26 and the exterior face of the sleeve, as indicated at 27. The baffle 26 has its larger upper end of 110 greater diameter than the opening 25. Secured to the cylinder wall is an inverted

trunco-conical sleeve 28 similar to the sleeve 22 and having its open lower end 29 arranged above the upper end of the inverted conical baffle 26. If desired, the structure hereinbefore described, including the trunco-conical sleeves 22 and 28 and interposed baffle 26, may be repeated above the baffle 26, as illustrated, although a single set of such sleeves and baffle is ordinarily sufficient.

10 In installing the device, the band 13 is mounted upon the stack after the two U-shaped retaining members 14 have been applied to the stack at diametrically opposed points upon the rolled edge 12 thereof. This band is tightened upon the flanges 16 so as to hold these members immovable. To one of the supporting bars 20 of the cylinder 10 one pair of the eyes 18 is permanently pivotally connected by means of a pintle 30, while the other eyes 18 are connected with the eye 19 by a removable pin 31, so that this pin may be removed to permit the spark arrester to be swung to folded or inoperative positions upon the stack, as shown in dotted lines in Figure 1. During the operation of the engine, gas blown from the stack will enter the lower end of the cylinder which, as shown, is of greater diameter than the stack and will be converged by the trunco-conical sleeve 22 and cause it to impinge against the baffle plate 26 by which the gases are diverged, together with the cinders carried thereby, and directed upwardly into the angle 32 between the inverted trunco-conical sleeve 28 and the wall of the cylinder 10. Here the gases substantially come to rest, finally passing through the opening between the lower end of the inverted trunco-conical sleeve 28 and the baffle 26, and passing upwardly through the opening 29 of the inverted conical sleeve 28 to escape, or, if a second series of sleeves and baffle be provided, to pass through such series where the sequence above given is repeated. In 45 the angle 32, where the gases come to rest, the cinders drop by gravity upon the upper outer surface of the conical sleeve 22 and are directed downwardly and outwardly thereby to pass through the openings 24. In order that cinders may not lodge between the walls of the sleeve 22 and cylinder 10 intermediate the openings 24, I provide intermediate the edges of the openings between the wall of the cylinder and 50 the walls of the sleeve 22 wedge portions 33 fitting at their outer edges against the walls of the cylinder 10 and at their inner edges against the walls of the baffles, the peaks of these wedge portions being upwardly directed and arranged substantially centrally between adjacent edges of openings

24. It will be obvious that a structure of this character may be very cheaply and readily produced and is quite as readily and cheaply attached to the locomotive.

It will furthermore be obvious that this structure is capable of a certain range of change and modification without materially departing from the spirit of my invention, and I accordingly do not limit myself to such specific structure as hereinbefore set forth except as hereinafter claimed.

I claim:—

1. In a spark arrester and in combination with a smoke-stack, a cylinder of greater diameter than the smoke-stack, means for supporting the cylinder in spaced and axial relation to the stack, the cylinder being provided adjacent the lower end thereof with a plurality of circumferentially spaced openings, a frustro-conical sleeve secured to the cylinder at its downwardly directed larger end immediately below the lower edges of said openings, an inverted conical baffle supported above the open smaller end of said sleeve, and an inverted frustro-conical sleeve secured to the cylinder above and in spaced relation to the upper end of said baffle.

2. In a spark arrester and in combination with a smoke-stack, a cylinder of greater diameter than the smoke-stack, means for supporting the cylinder in spaced and axial relation to the stack, the cylinder being provided adjacent the lower end thereof with a plurality of circumferentially spaced openings, a frustro-conical sleeve secured to the cylinder at its downwardly directed larger end immediately below the lower edges of said openings, an inverted conical baffle supported above the open smaller end of said sleeve, an inverted frustro-conical sleeve secured to the cylinder above and in spaced relation to the upper end of said baffle, and baffles connecting the first named sleeve and the wall of the cylinder intermediate the openings for directing cinders downwardly and outwardly to the edges of the openings.

3. Means for supporting a spark arrester upon the upper ends of stacks having rolled extremities comprising a plurality of U-shaped members straddling the rolled edge of the stack and each provided with downwardly extending portions, a clamping band surrounding the stack and securing thereto the downwardly extending portions of the U-shaped members, and means at the upper end of the U-shaped members for attachment to the spark arrester.

In testimony whereof I hereunto affix my signature.

CHARLES DE KOCK.
